CLAIM

The ornamental design for a tire sidewall, substantially as shown and described.

DESCRIPTION

FIG. 1 is a perspective view of a repetitive unit for a tire sidewall of our new design;

FIG. 2 is a right side elevational view of a first embodiment of our new design of FIG. 1 where the openings in the sidewall pass entirely through the tire and have indeterminate depth, the left side elevational view being a mirror image thereof; and,

FIG. 3 is a right side elevational view of a second embodiment of our new design of FIG. 1 where the openings in the sidewall do not pass entirely through the tire and have indeterminate depth, the left side elevational view being a mirror image thereof.

The broken lines in the figures above depict portions of the article that are not part of the claimed design.

The broken lines in the drawings represent unclaimed environmental subject matter.
